UNITED STATES PATENT OFFICE.

WALTER H. CLARKE, OF ELYRIA, OHIO.

DESIGN FOR A TIRE.

54,599.

Specification for Design.

Patented Mar. 9, 1920.

Application filed June 19, 1919. Serial No. 305,434. Term of patent 7 years.

To all whom it may concern:

Be it known that I, WALTER H. CLARKE, a citizen of the United States, residing at Elyria, in the county of Lorain and State of Ohio, have invented a new, original, and ornamental Design for a Tire, of which the following is a specification, reference being had to the accompanying drawings, forming a part thereof.

In said drawing, Figure 1, is a plan view

of a portion of a tire embodying my new design and Fig. 2 is a vertical section through the tire.

I claim:

The design for a tire substantially as shown.

WALTER H. CLARKE.
